United States Patent Office

Des. 188,124

Patented June 7, 1960

188,124

ABRADING TOOL

William E. Cowley and Wilfred M. McCord, Jr., Louisville, Ky., assignors to American Saw and Tool Company, Louisville, Ky., a corporation of Kentucky

Filed July 10, 1958, Ser. No. 51,725

Term of patent 14 years

(Cl. D37—1)

Figure 1 is a perspective view of an abrading tool showing our new design;

Figure 2 is a side elevational view thereof, both sides being of similar appearance;

Figure 3 is a top plan view thereof;

Figure 4 is an end view thereof taken from the right hand side of Figure 3; and

Figure 5 is an end view of the abrading tool taken from the left hand side of Figure 3.

The dominant features of the design reside in the portions shown in full lines.

We claim:

The ornamental design for an abrading tool, substantially as shown and described.
